UNITED STATES PATENT OFFICE.

CARL W. WEISS, OF NEW YORK, N. Y.

INTERNAL-COMBUSTION ENGINE.

1,150,084.

Specification of Letters Patent. Patented Aug. 17, 1915.

Application filed July 25, 1914. Serial No. 853,015.

To all whom it may concern:

Be it known that I, CARL W. WEISS, a citizen of the United States, residing in the borough of Brooklyn of the city of New York, in the State of New York, have invented certain new and useful Improvements in Internal-Combustion Engines, of which the following is a specification, reference being had to the accompanying drawing, forming a part hereof.

This invention relates to internal combustion engines in which the fuel oil is injected into the combustion chamber and is there vaporized and mixed with the air to form the charge and more especially to engines of this class in which the heat generated by the compression of the charge is mainly relied upon to produce ignition.

The invention is particularly concerned with the mechanical device by which the oil, injected under high pressure and at great velocity, is broken up into spray and vaporized, and consists in an improved spraying and vaporizing device.

The invention will be more fully explained hereinafter with reference to the accompanying drawing, in which it is illustrated, and in which—

Figure 1 is a view in longitudinal section of an internal combustion engine which embodies the invention, some of those parts which are not necessary to an understanding of the invention being omitted. Fig. 2 is a top view of the means, of well known construction, which may be employed to inject the oil into the combustion chamber. Fig. 3 is a detail view in section showing the improved spraying and vaporizing device in relation to the nozzle through which the oil is injected. Fig. 4 is a top view of the spraying and vaporizing device removed from its seat.

The engine, as shown in the drawing, may be of ordinary construction, except so far as the spraying and vaporizing device is concerned. As shown, the working cylinder and combustion chamber A is provided with a trunk-piston B connected by a pitman B' with a crank shaft C. The crank-chamber A² is inclosed, as usual, to permit the compression by the forward stroke of the piston of the air required for the formation of each charge. The cylinder is also provided, as usual, with an inlet port a communicating with the crank-chamber A¹

and arranged to be uncovered by the piston as it approaches the limit of its forward movement, and with an exhaust port a', also arranged to be uncovered by the piston, preferably slightly in advance of the inlet port a. The cylinder is also provided, as usual, with an inlet port a² to admit air to the compression chamber A² as the piston approaches the limit of its rearward movement. The cylinder A, as well as its head A³, is water-jacketed.

The fuel pump G, operated from the crank shaft C in the usual manner, is constructed and arranged so as to deliver the fuel oil, under high pressure and with great velocity, through a suitable nozzle g into the combustion chamber. The nozzle g is conveniently located in the wall of the head A³ of the cylinder and injects the oil into a recess a⁴ in such head. Opposite the nozzle g, and seated freely in a seat a⁴ formed therefore in the head A³ is the improved spraying and vaporizing device D. This comprises a central body d, which preferably has sufficient mass to retain the heat well when it has once become heated, and fits freely in its seat a⁴, so that it shall be to some extent insulated from the water-jacket and therefore shall not cool off as rapidly as it might otherwise. The upper or outer end of the body d is formed with a flat face d' in a plane at right angles to the axis of the nozzle g and co-axial therewith. From the central body d, at or near its upper end, extend radially integral arms d², which support a ring d⁴, formed integral therewith, the inner face d⁵ being at right angles to the plane of the face d' of the body d and extending slightly above and below such plane.

In the operation of the engine, when the body d has become thoroughly heated, the fuel oil, injected through the nozzle g, under great pressure and at high velocity, impinges violently upon the flat face d' of the body d and is broken up into a fine spray and also vaporized to some extent through contact with the heated body d. The finely divided particles of oil fly off, also at a high velocity, in a plane or planes substantially at right angles to the axis of the nozzle g, and impinge violently upon the inner face d⁵ of the ring d⁴, whereby the oil is still further broken up and vaporized. By such means the vaporization of the oil is carried practically to a degree of perfection and the

quality of the resultant mixture with the air is improved and the efficiency of the engine increased.

It will be obvious that the form of the vaporizer may be changed more or less to suit different conditions of use and that the invention is not limited to the particular form shown nor to its precise arrangement in the combustion chamber.

10 I claim as my invention:

1. In an internal combustion engine, the combination with a fuel nozzle and means to inject the fuel oil through the same under high pressure and at great velocity, and a spraying and vaporizing device located in the path of the oil having a flat face upon which the oil impinges at right angles and a ring surrounding the flat face in the same plane therewith and against which the particles of oil dashed from such flat face may impinge violently.

2. In an internal combustion engine, the combination with a fuel nozzle and means to inject the fuel oil through the same under high pressure and at great velocity, and a spraying and vaporizing device comprising

a central body with a flat face against which the oil is ejected at right angles, integral, radial arms, and an integral ring in the same plane with said flat face supported by said arms and against the inner face of which particles of oil from the face of the central body are dashed violently. 30

3. In an internal combustion engine, the combination of a combustion chamber, a fuel nozzle projected through the wall thereof, means to inject the oil under high pressure and at great velocity, and a spraying and vaporizing device seated freely in the wall of the combustion chamber opposite the fuel nozzle, such device having a flat face against which the fuel oil impinges violently, and an integral ring surrounding the flat face in the same plane therewith and against which the particles of oil are dashed 40 from such flat face. 45

This specification signed and witnessed this 24th day of July, A. D. 1914.

CARL W. WEISS.
